C. E. REDDIG

CLUTCH MECHANISM

Filed May 1, 1920

Inventor:
Charles E. Reddig.
by *Hubert A. Patterson*.
Att'y.

UNITED STATES PATENT OFFICE.

CHARLES E. REDDIG, OF RICHMOND HILL, NEW YORK, ASSIGNOR TO WESTERN ELECTRIC COMPANY, INCORPORATED, OF NEW YORK, N. Y., A CORPORATION OF NEW YORK.

CLUTCH MECHANISM.

Application filed May 1, 1920. Serial No. 378,142.

To all whom it may concern:

Be it known that I, CHARLES E. REDDIG, a citizen of the United States, residing at Richmond Hill, in the county of Queens, State of New York, have invented certain new and useful Improvements in Clutch Mechanisms, of which the following is a full, clear, concise, and exact description.

This invention relates to improvements in clutch mechanisms, the primary object being to provide a clutch mechanism having simple and efficient means for moving one of a plurality of operatively connected driven elements into and out of operative connection with a driving element.

The present improved clutch mechanism is especially adapted for use in a vacuum cleaner of the type employing an electric motor and a rotatable brush, the clutch mechanism serving to couple and uncouple the driving mechanism for the brush from the electric motor, but it is to be understood that this clutch mechanism is not confined to such an application but may be employed for a variety of uses without departing from the spirit and scope of the invention.

In the embodiment of the invention illustrated in the drawings and described in detail in the specification, the improved clutch mechanism is disclosed as applied to an electric vacuum cleaner and comprises a worm in axial alignment with the armature shaft of the electric motor of the vacuum cleaner, this worm having in constant mesh therewith a worm gear which actuates a shaft carrying a pulley for driving the brush of the vacuum cleaner. A manually operable sliding sleeve supports the worm and serves when actuated to couple or uncouple the worm from the armature shaft of the motor without unmeshing the worm from the worm gear.

Other features of the present improvement are described in detail in the specification and illustrated in the accompanying drawings, in which Fig. 1 is a top plan view showing an electric vacuum cleaner embodying the improved clutch mechanism, part of the dust bag, operating handle and casing being broken away.

Fig. 2 is an enlarged fragmentary side elevation, partly in section, showing in detail the construction of the worm and the manually operable sliding sleeve for cou-

pling and uncoupling the worm from the armature shaft of the motor.

Fig. 3 is a reduced vertical sectional view taken on the line 3—3 of Fig. 2 and looking in the direction indicated by the arrows.

Referring now to the drawings in detail in which like reference numerals designate similar parts throughout the several views, 1 illustrates the casing of a vacuum cleaner of well known construction, having at one end a nozzle 2 within which a brush 3 is rotatably supported. Within the casing 1 and in rear of the brush 3, a fan (not shown) is provided which is actuated by an electric motor (also not shown), the fan sucking dust from the nozzle 2 and brush 3 upwardly into a dust bag 4, all of which construction is of well known design and is not thought to need further description. The casing 1 is mounted upon suitable wheels 5 so that it may be moved from place to place by means of a handle 6 secured to a yoke 7 which is suitably pivoted to the casing 1.

In the vacuum cleaner illustrated in the drawings, the electric motor (not shown) has its armature shaft 8 horizontally disposed and projecting rearwardly within a horizontally disposed housing 9 in axial alignment therewith. The interior of the housing 9 is made cylindrical and of a diameter to receive a cylindrical sleeve 10, provided on its inner end with a vertically disposed annular rim 11 against the inner face of which an outer ring 12 of a ball race is fitted. A spacing sleeve 13 is positioned between the ring 12 and an outer ring 14 of a second ball race. The inner surface of the sleeve 10 is provided with internal screw threads to mesh with external screw threads formed on the outer periphery of a hollow hub portion 15 made integral with a knob 16 which serves as a means for manually operating the clutch mechanism as will be hereinafter described in detail. The inner edge of the hub 15 is adapted to fit against the outer edge of the ring 14 and when the knob 16 is screwed inwardly into the position illustrated in Fig. 2, the hub portion 15 thereof clamps the ring 14, spacing sleeve 13 and ring 12 tightly between it and the annular rim 11 formed on the inner end of the sleeve 10 so that the rings and spacing sleeve are locked to the sleeve 10.

operating with each of the rings 12 and 14 are balls 18 which run in groove formed in the said rings and in grooves formed in inner rings 19 and 20 which are mounted upon a horizontally disposed shaft 22 and spaced by a spacing sleeve 23. A shoulder 24 is formed on the shaft 22 adjacent the inner edge of the ring 19 and a nut 25 screwed on the threaded outer end of the shaft securely clamps the rings 19 and 20 and the spacing sleeve 23 between it and the shoulder 24 so that the rings and spacing sleeve rotate with the shaft 22. A worm 26 made of steel is made integral with the shaft 22 and is provided with a central bore 27 to receive the end of the armature shaft 8, when the parts are positioned as illustrated in Fig. 2, and is also provided with spaced clutch lugs 28 to receive between them a pin 29 which extends through the armature shaft 8 and projects beyond each side thereof at right angles.

When the parts are in the positions illustrated in Fig. 2, the worm gear is in driving connection with the armature shaft 8 so that when the electric motor is set in motion, the worm 26 and integral shaft 22 will be rotated, the latter carrying with it the rings 19 and 20 which revolve against the balls 18. The rings 12 and 14, sleeve 10 and knob 16 are held against rotation by means comprising a disk 30 surrounding the hub 15 and clamped between the inner face of the knob 16 and the outer edge of the sleeve 10, the disk 30 being provided with a horizontally disposed tongue 31 fitting between spaced lugs 32 formed on the casing 9 and having a triangular shaped struck up portion 33 to engage with a lug 34 having oppositely inclined faces and cast integral with the casing 9. When it is desired to uncouple the worm 26 from the armature shaft 8 of the motor, the hand knob 16 is moved to the right, as viewed in Fig. 2, carrying with it the sleeve 10, the inner and outer rings of the ball races, the spacing sleeves 13 and 23, the shaft 22 and the worm 26. The knob 16 is moved outwardly a distance sufficient to move the triangular struck up portion 33 on the tongue 31 into contact with the rear inclined surface of the lug 34, the end of the spring 31 being enlarged at 35 so that it will engage with the lugs 32 and prevent further rearward movement of the tongue 31 and consequently the knob 16. The movement of the knob just described is sufficient to disengage the driving connection between the worm 26 and the armature shaft 8 of the motor. To engage the worm 26 with the armature shaft 8 of the motor, the knob 16 is moved inwardly until the parts assume the positions illustrated in Fig. 2, the inward movement of the knob 16 and sleeve 10 being limited by the engagement of the end of the sleeve 10 with an annular

shoulder 35' formed on the inner wall of the casing 9.

In constant mesh with the worm 26 is a fiber worm gear 36 (Fig. 3) secured to a downwardly extending shaft 37 rotatably mounted within suitable bearings 38 carried by a bracket 39 made integral with the casing 9. A pulley 40 is secured to the lower end of the shaft 37 which drives a belt 41 connecting the pulley 40 and a second pulley 42 secured to the rotatable brush 3. Since the worm 26 and fiber worm gear 36 are in constant mesh, when the former is slid longitudinally through an actuation of the knob 16 to disconnect it from the armature shaft 8 of the motor, this sliding movement necessarily causes a partial rotation of the worm gear 36, shaft 37, pulley 40 and brush 3. The brush 3 rotates very easily so that this partial rotation, due to the actuation of the worm gear 36, causes no appreciable drag against the movement of the worm 26. However, if the brush 3 is in contact with the carpet, or should by any means be held against rotation, when the worm 26 is slid horizontally causing a partial rotation of the worm gear 36, the pulley 40 will slip within the belt 41.

No means is provided for lubricating the steel worm 26 and the fiber worm gear 36, but the ball races within the sleeve 10 are packed with grease which is prevented from leaking out of the outer end of the sleeve 10 by means of the meshing screw threads on the hub 15 and the sleeve, the inner end of the sleeve being oil tight through the provision of a packing washer 43 which surrounds an enlarged portion of the shaft 22 and engages the inner peripheral edge of the rim portion 11 of the sleeve 10.

What is claimed is:

1. A clutch mechanism for vacuum cleaners having a rotatable brush and an electric motor, comprising a casing, a worm slidably in said casing into and out of operative connection with the armature shaft of said motor, a worm gear meshing with said worm, a brush actuating mechanism operatively connected with said worm gear, and a sliding sleeve operatively connected with said worm and disposed in said casing for sliding said worm into and out of operative connection with the armature shaft of said motor.

2. A mechanism of the class described comprising a driving element, a movable driven element in axial alignment therewith, a fixed driven element disposed at an angle and operatively connected with said movable driven element, a bearing for said movable driven element comprising a ball race disposed in a substantially oil-tight sleeve, and means for sliding said bearing to carry said element into and out of operative connection with said driving element.

3. A clutch mechanism for vacuum cleaners having a rotatable brush and an electric motor, comprising a rotatable driven element movable into and out of operative connection with said motor, a rotatable element for actuating said brush and operatively connected with said driven element, a bearing for said driven element comprising a ball race disposed in a substantially oil-tight sleeve, and means for moving said bearing to move said driven elements into and out of operative connection with said motor.
- In witness whereof I hereunto subscribe my name this 27th day of April, A. D., 1920.

CHARLES E. REDDIG.
